MYRON MACY KINLEY, OF TULSA, OKLAHOMA

METHOD OF AND APPARATUS FOR DETERMINING INCLINATION OF WELL HOLES

Application filed April 2, 1930. Serial No. 441,051.

My invention relates to a method of and apparatus for determining the inclination of well holes and has for its principal object to provide a method and apparatus whereby such determination may be effected intermittently while a well is being drilled without loss of time in the drilling operation.

In drilling wells with rotary tools it is not unusual for the drill bit to be deflected by inclined strata or from other causes to an extent sufficient to cause substantial inclination of the hole; in some cases successive variations resulting in irregular inclinations which may seriously interfere not only with continued drilling but also in subsequent pumping of the well. It is therefore desirable for the driller to check the direction of the hole from time to time as the drilling proceeds.

Various methods and apparatus have been provided for this purpose, one of which includes lowering a bottle of acid into the hole to the point to which drilling has progressed and retaining the bottle stationary for a sufficient period for the acid to etch the inner surface of the bottle, then removing the bottle and determining inclination of the hole from angularity of the line of etching on its inner surface. While this method provides substantially accurate reading of the hole, it interrupts the drilling operation, as the tools must be removed from the well while the reading is being taken.

With my method, however, the acid bottle may be let into the well with the tools, the acid drained from the bottle after the etching has been made and the bottle left in the well to be removed with the tools when the latter are taken from the well for replacement or repair in accordance with ordinary drilling practice, so that the only delay is that occasioned by installation and drainage of the acid bottles.

In accomplishing the above stated and other objects of my invention, I have provided improved details of structure, the preferred form of which is illustrated in the accompanying drawings, wherein:

Fig. 1 is an elevational view of a rotary drill bit in the process of drilling a well hole,

the drill pipe being partly broken away to show my improved inclinometer mounted therein.

Fig. 2 is a central longitudinal section of the inclinometer mounted in a drill pipe portion with the acid bottle in position for recording the degree of incline of the well hole.

Fig. 3 is a detail perspective view of the inclinometer parts in disassembled relation.

Fig. 4 is a longitudinal section of the acid bottle.

Referring more in detail to the drawings:

1 designates a well hole being drilled by a rotary bit 2 driven from the usual rotary draw works (not shown), by a string of drill pipe, formed of sections 3.

Interposed between the lower end of the pipe string and a section 4 connected to the drilling bit, is a relatively short pipe section 5 having a threaded pin end 6 engaging the upper box end 7 of the coupling, the upper internally threaded box end 8 of the pipe section receiving the lower pin end of the drill pipe.

In order to receive the apparatus embodying my invention and generally designated 9, the flow channel 10 of the short pipe section is counterbored throughout the greater portion of its upper end to provide a chamber 11 terminating in a lower stop wall 12 for seating a supporting ring 13 securely held in the chamber by a set screw 14, threaded into a lateral opening 15 in the pipe wall. Both the inner wall of the ring and the adjacent portion of the flow channel are tapered to prevent excessive retardation of fluid flowing therethrough.

The supporting ring further includes integral spider arms 16 fixed to a concentric bearing portion 17, having a hexagonal opening 18 counterbored at its upper end for forming a conical bearing seat 19 to rotatably support a housing 20, having integral spiral ribs 21 on its outer surface, constituting propellers whereby the housing may be rotated by force of drilling fluid passing through the drill pipe.

The upper and lower ends of the housing are internally threaded to receive respec-

tively the reduced threaded ends of conical closure caps 22 and 23, the lower one of which has point bearing on the seat 19.

Formed integrally with the housing substantially midway thereof is a partition wall 24 having a concentric opening 25 and a counterbored socket 26 for seating the lower end of an inverted acid bottle 27, the upper end of which extends into an aligning socket 28 in the closure cap 22.

For effecting rotation of the body member to discharge contents of the acid bottle, the lower closure member is provided with a concentric opening 29 to screw threadedly 15 receive a stem 30 having a lower hexagonal end 31 slidably projected into the opening 18 of the spider ring 17. Fixed on the upper unthreaded end 32 of the stem by a screw 37 and aligning with and slightly spaced 20 from the cork 33 of the acid bottle, is a collar 34 having a conical lower face 35 normally seated in a conical recess 36 of the closure cap 23.

To facilitate removal of the apparatus 25 from the drill pipe a screw eye 38 may be threaded into an opening 39 of the upper closure cap.

Attention is particularly directed to the construction of the acid bottle. As illustrated in Fig. 4, approximately the lower 30 half of the bottle is lacquered interiorly with a preparation 40, impervious to acid, so that etching of the bottle is impossible when the bottle is in upright position. However, when 35 the bottle is inverted and retained in stationary position through a period of several minutes, etching of the bottle will result in direct conformation to the liquid in the bottle.

40 Assuming the apparatus to be constructed and assembled as described, the procedure for determining and recording the degree of inclination of a well hole is as follows:

A bottle containing a small quantity of 45 etching or recording fluid is mounted in inverted position in the housing 20, and the hexagonal head of the stem 30 is inserted in the cooperating socket of the supporting bracket. The short pipe section is then interposed in the string of drill pipe near its 50 lower end and the string of pipe and attached bit are lowered to the bottom of the hole.

Upon reaching the bottom of the hole, the 55 drill pipe is retained in stationary position for a period of several minutes to allow etching of the fluid into the bottle. Drilling fluid is then turned into the drill pipe and as it engages the blades on the body member the housing 20 is rotated, and threaded onto the 60 fixed stem, projecting the upper end of the stem into contact with the stopper, thereby forcing the cork into the bottle and discharging the contents.

Thereupon drilling is begun in the usual 65 manner and continued until it becomes necessary to pull the pipe string and drilling bit from the bore of the well.

Each time the bit reaches the top of the well any existing degree of inclination of the hole is ascertained from the etching in the 70 bottle upon removing the bottle from the inclinometer housing.

A duplicate bottle containing a fresh supply of acid or other recording fluid is then 75 mounted in the inclinometer and the drill and pipe string are again lowered into the well for further drilling.

Due to the rugged construction of the apparatus it is possible to maintain the instrument in the drill pipe throughout the process 80 of drilling and an accurate check on the condition of the well hole is continually available.

What I claim and desire to secure by Letters Patent is:

1. The method of determining inclination of a well hole including lowering a receptacle containing marking fluid into a well hole, retaining the receptacle in the hole undisturbed for a period sufficient to permit the marking fluid to act on the receptacle, introducing a drilling fluid into said well hole, and causing the movement of said fluid to open the receptacle in the hole to permit discharge of the fluid. 95

2. The method of determining inclination of a well hole including lowering a receptacle containing marking fluid into a well hole, retaining the receptacle in the hole undisturbed for a period sufficient to permit the marking fluid to act on the receptacle, introducing a drilling fluid into said well hole, causing the introduction of said fluid to rotate said receptacle, thereby opening the receptacle in the hole to permit discharge of the fluid, and removing the receptacle from the well hole for observation. 100

3. Apparatus of the character described including relatively fixed and rotatable members adapted for mounting in a drill pipe, an inverted receptacle carried by one of the members, a fluid adapted to be injected into said drill pipe and brought into contact with the rotatable member for rotating the same, and means connected with the other member for effecting discharge of contents of the receptacle in response to rotation of the rotatable member. 110

4. Apparatus of the character described including a bracket adapted for non-rotatable mounting in a drill pipe, a housing mounted on the bracket and including means for effecting rotation of the housing in response to flow of drilling fluid through the pipe, an inverted container for marking fluid fixed in the housing, a stopper for the container, a screw fixed to the bracket in threaded relation with the housing engageable with the stopper in response to rotation 115 120 125 130

of the housing for effecting removal of the stopper to drain the container.

5. In combination with drill pipe, a housing in the pipe adapted to remain in said pipe during the drilling operation, a container in the housing, marking fluid in the container, and means on the housing responsive to fluid passing through the drill pipe, for rotating the housing to effect discharge of said marking fluid from the container. 70

6. In combination with drill pipe, a housing in said pipe, a container in the housing, marking fluid in the container, a non-rotatable member threaded into the housing and aligning with said container, and means responsive to fluid passing through the drill pipe for rotating the housing relative to said non-rotatable member to effect discharge of said marking fluid from the container. 75

7. In combination with a drill pipe, a housing in said pipe, a container in the housing, recording fluid in the container, a fixed stem threaded into the housing and aligning with said container, and means responsive to fluid passing through the drill pipe for rotating the housing on said stem to effect discharge of said recording fluid from the container. 80

8. In combination with drill pipe, a housing in said pipe, a container in the housing, recording fluid in the container, a stem threaded into the housing and aligning with said container, means for slidably mounting the stem and preventing rotation thereof, and spiral blades on said housing responsive to fluid passing through the drill pipe for rotating the housing on said stem to effect discharge of said recording fluid from the container. 85

9. In combination with drill pipe, a housing in said pipe, a container in the housing, recording fluid in the container, a stem threaded into the housing and aligning with said container, a bearing bracket in the drill pipe for rotatably supporting the housing and having an opening for slidably receiving the stem, and spiral blades on said housing responsive to fluid passing through the drill pipe for rotating the housing on said stem to effect discharge of said recording fluid from the container. 90

10. In combination with drill pipe, a housing in said pipe, a container in the housing, recording fluid in the container, a stem threaded into the housing and aligning with said container, a polygonal head on the stem, a bearing bracket in the drill pipe for rotatably supporting the housing and having a polygonal opening for slidably receiving said head, and spiral blades on said housing responsive to fluid passing through the drill pipe for rotating the housing on said stem to effect discharge of said recording fluid from the container. 95

11. In combination with drill pipe, a hous-

ing in said pipe, an inverted acid container in the housing, a stopper in said container, a stem threaded into the housing and aligning with said stopper, a polygonal head on the stem, a bearing bracket in the drill pipe for rotatably supporting the housing and having a polygonal opening for slidably receiving said head, and spiral blades on said housing responsive to fluid passing through the drill pipe for rotating the housing on said stem to force the stopper into the container. 100

In testimony whereof I affix my signature.
